UNITED STATES PATENT OFFICE.

HENRY E. WILKINS AND JOSEPH L. DOLE, OF SPRINGFIELD, MASS.

HEEL-IRON.

SPECIFICATION forming part of Letters Patent No. 271,755, dated February 6, 1883.

Application filed June 9, 1882. (No model.)

To all whom it may concern:

Be it known that we, HENRY E. WILKINS and JOSEPH L. DOLE, citizens of the United States, residing at Springfield, in the county of Hampden and State of Massachusetts, have invented new and useful Improvements in Heel-Irons, of which the following is a specification.

Our invention is a heel-iron constructed, as fully described hereinafter, so as to secure a continuous solid iron or frame, yet applicable to heels of different shapes and sizes.

In the drawings, Figure I is a face view of a heel with our improved iron applied thereto. Fig. II is a view showing the parts of the iron detached, and Fig. III is a side view of Fig. I.

The iron consists of two curved plates, D D', each having two perforations, h d.

One end of each plate is depressed or cut away for half its depth, so that when the two are applied with their ends overlapped a hinge-joint is formed with the faces of both plates on the same planes, and the hole h in the plate D is countersunk, so that when the plates are connected to each other and to the heel by a screw or pin, b, as shown in Figs. I and III, there will be no projection beyond the outer surface of the plate. After securing the ends of the plate together and to the heel, as described, the plates are brought together or spread apart

until their edges coincide with those of the heel, when other screws or pins are passed through the holes d, and the plates thereby firmly secured.

We are aware that two plates—one recessed to receive the rounded end of the other—have been applied to heels; but in such case there is no continuous plate, the introduction of nails, stones, &c., between the joints is apt to loosen them and force them apart, while the rigidity imparted by a continuous plate is not secured.

By the above structure the plate is rendered practically continuous, but capable of being applied to heels of different sizes, while it can be secured more firmly with less screws than when the sections are separated.

We claim—

An improved heel-plate, consisting of two sections or plates adapted to have their recessed ends hinged or connected by means of the attaching-screw, whereby the plates may be made to conform to heels differing in size, and provided with perforations at their free ends, all substantially as set forth.

HENRY E. WILKINS.
JOSEPH L. DOLE.
